(57) **CLAIM**

The ornamental design for an apple shape paper box, as
shown and described.

DESCRIPTION

FIG. 1 is a perspective view of an apple shape paper box
showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is another perspective view showing the apple shape
paper box.

FIG. 9 is the other perspective view showing the apple shape
paper box; and,

FIG. 10 is an exploded perspective view showing the apple shape
paper box.

The broken lines shown represent unclaimed subject matter
and form no part of the claimed design.
